Des. 1796

Henry W. Kneel, of Philadelphia, Pa.
Letters Patent No. 1796. Dated July 7th 1863.

The schedule referred to in these ^{num} Letters Patent and making part of the same,
^{numnum}

To all whom it may concern:

Be it known that I, Henry W. Kneel, of Philadelphia, County of Philadelphia, State of Pennsylvania, have invented or produced a new and original design for blind binding; and I do hereby declare the accompanying drawing with the following explanation of the same, to form a full, clear and exact description of the said design.

Each edge of the binding is ornamented with a border consisting of a row of crosses with intervening dots.

On the binding between the borders are a series of patterns A, situated a short distance apart from each other and at uniform intervals.

Each pattern A, consists of four scrolled and foliated ornaments inclosing or nearly inclosing a space containing an ornament of the form represented in the drawing.

The spaces between the patterns A, are ornamented, each space with a device B, clearly indicated in the drawing.

I claim and desire to secure by Letters Patent, the ornamental figures and forms represented in and by the accompanying drawing, the whole forming an ornamental design for blind binding.

In testimony whereof I have signed my name to this specification in the presence of two subscribing witnesses.
